UNITED STATES PATENT OFFICE

LAWRENCE O. BEARD, OF LANCASTER, PENNSYLVANIA

CHUCK

Application filed April 4, 1931. Serial No. 527,783.

My invention relates to chucks for reamers, drills and similar tools and particularly to that type of chucks employing a pair of oppositely arranged loosely mounted gripping jaws.

The object of the invention is to provide a pair of chuck jaws which will readily line up or center cylindrically shanked tools.

Another object is to provide an improved construction of jaws, whereby the cylindrical portion of the tool shank will be frictionally gripped and the squared end thereof will be positively gripped when the tool turns in the jaws under excessive driving pressure, incident to use on heavy work.

A further object is to provide a four point yielding bearing and a two point driving bearing for gripping the round and square portions of the tool shank respectively.

20 A still further object of the invention is to provide an improved arrangement and construction of oppositely disposed chuck jaws adapted to be moved to closed position with their acting faces maintained in parallel relation to each other.

I accomplish the above mentioned and other related objects by the improved construction hereinafter described and claimed.

Of the accompanying drawing forming a part of this specification:

Figure 1 represents a longitudinal section of a chuck having jaws embodying my invention applied to the shank of a reaming tool;

Figure 2 is a longitudinal sectional view 35 taken through Figure 1, with the reaming tool removed;

Figure 3 is similar to Figure 1 showing the spring means for maintaining parallel alinement of the jaws;

40 Figure 4 is a view similar to that shown in Figure 3, with the jaws in open position and cap removed;

Figure 5 is a transverse section on the line 5—5 of Figure 1, with the tool shank removed;

Figure 6 is a side view of one of the jaws; and

Figure 7 is an end view of one of the jaws.

Referring more particularly to the drawing wherein the same reference characters in-

dicate like parts in all the figures, 1 denotes the body of my improved chuck which is of cylindrical shape and formed at its outer or forward end with a nose portion 2. The body 1 is threaded exteriorly as at 3 for engagement with the internally threaded cap member 4, and is also provided with a centrally disposed bore or passage 5, adapted to receive the reduced threaded end 5' of the customary driving shaft or shank 6 by means of 60 which the chuck is attached to a source of power, such as a drill press, not shown.

The nose portion 2 of the body 1 is longitudinally slotted in a central plane as at 7, to form the jaw receiving prongs or portions 65 8 between which a pair of jaws 9 hereinafter described fit. The nose end is of frusto conical taper to fit the correspondingly tapered end 10 of the cap or clamping sleeve member 4.

The jaws 9 have flat exterior bearing surfaces 11 which slidably fit against corresponding surfaces 12 formed on the inner faces of the prongs 8, and a coiled spring member 13 which connects the two jaws together serves to resiliently maintain the latter in the slot 7 in normal open or Figure 4 position. The body of this spring lies within the enlarged central chamber of bore 14, formed in the body of the chuck, and the straight ends 15 thereof extend outwardly 80 through narrow slots or grooves 16 into the longitudinal slot 7, when they are attached to the inner ends of the jaws.

In accordance with the present invention, the inner clamping face of each jaw is formed 85 at its lower end portion with an elongated longitudinal substantially V-shaped recess or groove 18 of uniform width and depth throughout its length. The flat smooth sides 19 of the grooves diverge from each other at an angle substantially that of a right angle and present a four point yieldable gripping bearing adapted to conform to and line up or center the cylindrical shank portion 20 of the reamer or other tool 21, when the latter is inserted in the chuck and the cap member 4 is screwed home, in an obvious manner. To simplify machining the groove 18 may be slightly flattened at the point where the inner 90 100

edges of the sides 19 approach each other, as best illustrated in Figure 2.

The inner end of each jaw 9 is also formed with a second comparatively short longitudinal substantially V-shaped recess or groove 22 which is in effect a continuation of the groove 18. The only substantial difference between the inner and outer grooves 22 and 18 is that the latter is cut deeper than the former, 10 the width and depth of each groove 22 being uniform throughout but slightly less than that of the grooves 18. The sides 23 of the grooves 22, also extend at substantially right angles to each other and provide a two point 15 gripping bearing for the squared end 24 of the tool shank, the depth and width of the grooves 22 adapting them to grip the squared end with freedom for slight turning movement of the latter therein. Notches or cross 20 grooves 25 cut in the inner ends of the sides 19 of the recesses or grooves 18 provide stop shoulders 27 at the outer ends of the sides 23 of the grooves 22, against which the end portions or shoulders 28 of the cylindrical shank 25 portions 20 of the reamer 21 seats when the tool is inserted in the chuck.

In practice, when the work is extremely heavy the resistance set up causes the tool shank to slip or turn relatively to the smooth 20 gripping faces or sides of the jaws but this movement is stopped and the tool is thereafter positively driven when the squared end of the tool reaches the limit of its rotary movement in the recesses 22 and becomes 25 locked. This provision for limited relative movement of the tool with respect to the clamping jaws is important in that it obviates the necessity of serrating the gripping faces of the jaws with consequent damaging effect upon the reamer or other tool.

From the foregoing it will be seen that each jaw is adapted to first grip the cylindrical portion 20 of the tool shank, with frictional driving effect and finally grip the 45 squared end portion 24 with positive locking driving effect. A double or differential driving effect is thus obtained and the strain is distributed throughout the length of the tool shank which receives the greatest stress at its squared end where it is most adaptable to resist tearing or shearing action of the jaws.

With the chuck parts in Figure 4 position with the jaws forced outwardly by the expansive action of spring 13, screwing up of the cap 4 will cause the conical nose of the latter to engage the conical outer end or nose 26 formed on each jaw. Continued inward movement of the cap moves the outer ends 60 of the jaws inwardly, and as the spring 13 is normally forcing the inner ends of the jaws outwardly in opposition to the action of the cap, the clamping faces of the jaws will be parallel to each other during the final 65 movement. This action of the jaws causes an

effective centering and gripping of the tool shank.

Having thus described my invention what I claim as my invention is:

In a chuck, a pair of tool-shank engaging jaws, the inner face of each jaw being formed with inner and outer longitudinally disposed recesses, the opposing sides of the inner and outer recesses being at similar angles to each other to respectively engage the flat end faces 75 and the cylindrical portion of a tool shank and the sides of said outer recesses being notched at their inner ends, and the outer recess being deeper than the inner recess whereby the outer ends of the sides of the 80 inner recesses will serve as a stop for engagement with the end of the cylindrical portion of the tool shank.

In testimony whereof I affix my signature,

LAWRENCE O. BEARD.
